UNITED STATES PATENT OFFICE.

JUSTIN SCHWARZBART, OF BERLIN, GERMANY.

HOLDER FOR SNUFF AND THE LIKE.

1,129,022.

Specification of Letters Patent. Patented Feb. 16, 1915.

Application filed February 29, 1912. Serial No. 680,764.

To all whom it may concern:

Be it known that I, JUSTIN SCHWARZBART, subject of the German Emperor, residing at 22 Jüdenstrasse, Berlin, Germany, have invented certain new and useful Improvements 5 in Holders for Snuff and the like, of which the following is a specification.

The present invention relates to a holder of snuff powder.

10 The novel feature of the present invention consists in that this holder, which is made in a very handy form and may be conveniently carried in one's pocket, has a snuffing end, so that the holder can serve as a nasal inhaler. This snuffing arrangement 15 is adapted to the shape of the nose and may be easily and conveniently introduced into the nostrils.

20 In the accompanying drawing several constructional forms of the present invention are exemplified.

Figures 1, 2, 3 show a holder in two parts 25 with two nozzles. Figs. 4 and 5 are a special constructional form for powder snuff.

25 In Figs. 1, 2 and 3 the flat vessel is made of the cover *g* and the bottom *f* to form a flat receptacle. The flattened ends *h* have holes *i*, which register with each other when the parts *f* and *g* are assembled, and will 30 thereby admit of air entering into the space when the snuff powder is snuffed. The snuffing end consists of the nozzles *h* which are formed when the parts *f* and *g* are assembled. When not in use the nozzles are cov- 35 ered by the sleeve-shaped cap *d*.

In Figs. 4 and 5 is shown a constructional form, which is of particular importance for filling the holder with snuff. In the part *t* 40 is provided a partition *u*, which has a bore *v*. When the parts *t* and *w* are assembled a separate chamber is formed in the holder.

Into this chamber is placed a wad of cotton wool or the like, which will prevent the snuff powder from falling out through the openings *v* and *x* and on the other hand allow 45 of a passage of air in snuffing. The partition is necessary to prevent the cotton wool from being drawn out by the suction in snuffing and that too large quantities of snuff enter the nose.

The holder may be made of any suitable 50 material. It is essential that it is made of a flat shape and can be conveniently carried in one's pocket.

I claim:

A holder for snuff and the like comprising 55 a bottom member consisting of a flat piece having a substantially double V shaped end, an upwardly extending flange extending entirely around the perimeter of said flat piece, 60 said flange having an opening through it at the front end of the holder and an opening coinciding with each of the V shaped ends, and a top member consisting of a flat piece having a substantially double V shaped end, 65 a downwardly extending flange extending entirely around the perimeter of said top flat piece and provided with holes coinciding with the holes in the flange of the bottom member, said top member being constructed 70 to fit over the bottom member, and a cover constructed to fit over both of the double V shaped ends; said V shaped ends constituting nozzles constructed to fit into the nostrils. 75

In testimony whereof I have hereunto set my hand in presence of two subscribing witnesses.

DR. JUSTIN SCHWARZBART.
